[57] CLAIM

The ornamental design for a watch casing and bezel, as shown and described.

DESCRIPTION

FIG. 1 is a front elevational view of a watch casing and bezel showing my new design;
FIG. 2 is a left side elevational view thereof;
FIG. 3 is a rear elevational view thereof; and,
FIG. 4 is a right side elevational view thereof.
The broken-line showings of a watch band are for environmental purposes and form no part of the claimed design.
